UNITED STATES PATENT OFFICE.

EBERHARD KLEPPER, OF CRIMMITSCHAU, GERMANY.

APPARATUS FOR PRODUCING CRINKLED PAPER.

Application filed December 10, 1923. Serial No. 679,789.

To all whom it may concern:

Be it known that I, EBERHARD KLEPPER, a citizen of the Republic of Germany, residing at Crimmitzschau, Saxony, Germany, 5 have invented certain new and useful Improvements in Apparatus for Producing Crinkled Paper, of which the following is a specification.

My invention relates to apparatus for 10 producing a paper having a veined or crinkled appearance, suitable for use as a wall paper, and for other purposes.

An important object of the invention is 15 to provide an apparatus of the above mentioned character, so constructed that a veined or crinkled paper may be produced cheaply and quickly.

A further object of the invention is to 20 provide means for treating the paper after being subjected to the heating and drying action, for restoring its original lustre and appearance.

Other objects and advantages of the invention will be apparent during the course 25 of the following description.

In the accompanying drawings forming a 30 part of this specification, and in which like numerals are employed to designate like parts throughout the same,

Figure 1 is a central vertical longitudinal section through an apparatus employed in 35 the practice of my method,

Figure 2 is a plan view of a section of the completed product, and,

Figure 3 is a detail section through the same.

In the drawings, wherein for the purpose 40 of illustration is shown a preferred embodiment of my invention, the numeral 5 designates a supporting frame, embodying a table 6.

Arranged at one end of the frame 5, near 45 its lower end, is a cylinder 7, carrying a roll 8 of a backing sheet or strip, such as a suitably heavy paper or fabric. The cylinder 7 is detachably rotatably mounted upon arms or brackets 9, secured to the frame. The heavy backing sheet from the roll 8, designated 8', passes over the table top 6 50 and travels longitudinally thereof to the right.

The frame 5 is provided near its top and 55 at its left end with arms 10, detachably and rotatably supporting a cylinder 11, which carries the roll 12 of the rumpled or crinkled paper, such as tissue paper. Now this paper

may be rumpled or crinkled before being wound upon the cylinder 11, and it should not be drawn too tightly so that the crinkles or ripples would be smoothed out, as the 60 paper must be fed in the crinkled or rumpled condition to the upper surface of the backing sheet 8'. The crinkled paper 12', from the roll 12, first passes over an upper table 13, and then down about vertical rollers 14, 65 and continues in a horizontal direction in contact with the backing sheet 8', about a roller 15, as shown.

Arranged in the upper portion of the frame 5, near its left end, is a tank or receptacle 16, for holding the sizing or paste, which is in a suitably semi-fluid condition, whereby it may be discharged in a substantially uniform manner to the upper surface of the backing sheet 8'. This sizing or 70 paste is discharged from the lower end 17 of the tank 16, which may be provided with apertures of suitable fineness at its bottom. The bottom 17 extends for substantially the entire width of the backing sheet 8', as is 75 obvious. Supported in advance of the bottom or outlet 17 is a brush 18, which applies the sizing or paste evenly to the surface of the backing sheet 8'. This backing sheet is relatively stout or heavy and free 80 from crinkles. It is thus seen that this surface of the backing sheet, with the sizing or paste thereon, and while wet, receives the crinkled or wrinkled upper sheet or tissue paper 12'. These two layers of paper then 85 discharge from the roller 15, and are subjected to a suitable compression and heat, in a closed receptacle or chamber. Prior to the passage to the roller 15, the upper and lower sheets, while cemented together, and 90 damp or wet, travel over a trough 15', supported beneath the table 6. This trough projects beyond the edges of the table and holds aniline dye, which may be applied by hand to the upper surface of the damp 95 crinkled paper.

This heating means embodies a chamber 19, in which are three suitably supported rollers or cylinders 20, 21 and 22. These cylinders 20 and 22 are preferably in the 100 same horizontal plane, while the cylinder 21 is in a higher plane. The cylinders are covered with an asbestos sheet or facing 23, and a cover 24 of linen or other fabric so that the paper will not stick to the metal wall 105 of the cylinder, or burn. The cylinders are equipped with electrical heating means, such 110

as resistance coils 23, arranged therein. It is preferred that the first cylinder 20 be heated to a temperature of about 40° C., the second cylinder to a temperature of 70° C., and the third cylinder to a temperature of 90° C. The paper embodying the upper and lower sheets is passed beneath the cylinder 20, above the cylinder 21, and then beneath the cylinder 22. These cylinders are free to rotate and are turned by the pull upon the paper.

The paper passing from the chamber 19 next discharges into a closed chamber 24, in which are mounted rollers 25, at different elevations, so that the paper is made to travel in a plurality of runs through the same. The paper is drawn through the chamber 24 by passing about a cylinder or roller 26, and being wound upon a cylinder 27, which may be turned by a crank 28. It might be stated at this point that the invention is in no sense restricted to this method of advancing the paper, although it is believed to be satisfactory. The drying cylinders might be mechanically driven, if desired. Also the cylinder 11 carrying the crinkled or rumpled paper may be turned by hand, to relieve this paper of any strain, which would tend to uncrinkle the paper, or it might be mechanically driven. However, this roll of paper is light and will turn freely, and it is ordinarily not necessary to drive the same. When the paper passes from the heating rolls, it may be found that it has lost some of its healthy fresh appearance, or lustre, and I have found that this may be restored within the chamber 24 by circulating moist cold air in contact therewith. This is effected by means of a blower 29, the air discharging through the outlet 30.

In the use of the apparatus in the practice of my method, the backing sheet 8' is caused to travel longitudinally upon the table 6, and the upper crinkled sheet 12' is caused to travel longitudinally and is brought upon the upper surface of the backing sheet which is coated with the sizing or paste. These two sheets thus secured together are passed between the heating cylinders, and there

subjected to pressure and a gradually increasing heat, as they pass from one cylinder to the other. By the time the material discharges from the last cylinder 23, possessing the maximum heat, it is dry and then discharges into the chamber 24, wherein it is subjected to the action of moist cold air, which restores the fresh healthy appearance or lustre to the paper. The product is then wound upon the cylinder 27, which is shown as the means for effecting the longitudinal travel of the paper. The paper is ordinarily made with a margin at the edges, which must be cut off, and I also contemplate winding the paper from the cylinder 27 and re-winding the same in rolls of desired length, ready for being placed upon the market.

It is to be understood that the form of my invention herewith shown and described is to be taken as a preferred example of the same, and that various changes in the shape, size, and arrangement of parts of the apparatus may be resorted to, and also that changes may be made in the steps of the method, and their order, without departing from the spirit of my invention or the scope of the subjoined claim.

Having thus described my invention, I claim:

Apparatus for producing a crinkled paper, comprising a table, a support for the table, means for supporting a roll of backing paper near one end of the table to deliver the same to the upper surface of the table, a tank arranged above the table for feeding a sizing to the upper surface of the paper, means for supporting a roll of crinkled paper in a manner to deliver the same to the upper coated face of the backing paper, a heating chamber, a plurality of heated cylinders mounted within the chamber about which the paper travels, a restoring chamber having means therein for supporting the paper in a plurality of runs, and means for effecting a circulation of fresh cold air within the restoring chamber.

In testimony whereof I affix my signature.

EBERHARD KLEPPER.
